COMBINED HEATING AND COOLING APPARATUS

Harold F. Hagen, Dedham, and Samuel M. Anderson, Sharon, Mass., assignors to B. F. Sturtevant Company, Inc., Boston, Mass.

Application July 5, 1934, Serial No. 733,734

2 Claims. (Cl. 98—10)

This invention relates to methods and apparatus for the conditioning of air and relates more particularly to methods and apparatus for heating and cooling air which is circulated through railway passenger cars.

It is now becoming well known that human comfort requires that the air within an enclosure should be not only circulated to provide sufficient ventilation, but should in winter be warmed, with moisture added to maintain the proper relative humidity and in summer should be cooled, and moisture extracted from it to overcome the excessive humidity which is usually present.

While the conditioning of air for motion picture theaters, hotel, office and industrial buildings has been developed to a high degree in recent years, the air conditioning of vehicles, and particularly railway cars, has been more or less neglected, due, perhaps, to the peculiar problems involved and the many difficulties present. Among the difficulties which present themselves are the lack of space in a railway car, which already of necessity has had to accommodate the maximum of equipment in the minimum of space, the excessive refrigeration equipment which would have to be carried if the ordinary method of conditioning buildings were followed, the changing temperature conditions through which a railway car must pass, the cost of the equipment, and other difficulties.

While there have been several methods proposed for the distribution of conditioned air in railway passenger cars, most railway management prefer the use of longitudinal distribution ducts. Ordinarily the air conditioning apparatus is mounted in one end and in the roof zone of the car, longitudinal supply ducts extend down along the side of the car and overhead the passenger space, and are provided with a small number of spaced outlets through which the conditioned air is blown.

The difficulties with this arrangement in the past have been two-fold, namely, distribution and drafts. When the relatively few openings were made of sufficient size to permit a low outflow velocity, distribution was almost entirely uncontrolled and resulted in unequal delivery from the various openings. When these openings were made small enough to dam back the air flow, producing a static pressure in the duct, the velocities from the openings were too high and produced unpleasant drafts.

To secure both good distribution and low velocities in the final discharge, the outflow of the conditioned air is controlled, according to this

invention, in two steps, by having a small distributing outlet from the main duct through which the air flows at high velocities. It then strikes a distributing baffle and flows at substantially any desired velocity through its final opening into the car. This is accomplished by providing in addition to a main duct, a small distributing outlet or auxiliary duct. The conditioned air is built up under static pressure in the main duct and flows at high velocity into the auxiliary duct, where it strikes a distributing baffle and then flows at a low or substantially any desired velocity into the passenger space of the car.

According to another feature of the invention the recirculated air drawn into the air conditioning unit for reconditioning may be indrawn from either the roof zone or the floor zone. In summer, the recirculated air is drawn into the conditioning unit from the roof zone, and, in winter, is drawn into the unit from the floor zone. By indrawing the air from the floor line in winter and discharging it in the roof zone, a positive circulation is obtained which has not been done before, and which is highly desirable. In summer, when air is cooled, the recirculated air can be withdrawn from the roof zone and the cold air discharged in the roof zone, and adequate circulation be obtained, because of the tendency of the cold air to descend into the passenger space by gravity and the tendency of warm air to rise. According to this invention, dampers are provided to control the indrawing of the recirculated air at the floor line or in the roof area.

An object of this invention is to supply hot or cold air, as required, with adequate circulation and without undesired air movement.

Another object of the invention is to supply cold air in summer without drafts and warm air in winter with adequate circulation.

Other objects of the invention will be apparent from the following description taken together with the drawings.

The invention will now be described with reference to the drawings, of which:

Fig. 1 is a horizontal, sectional view of the air conditioning apparatus and a portion of the supply duct mounted in the railway car shown by Figs. 3 and 4;

Fig. 2 is a vertical section through the apparatus shown by Fig. 1;

Fig. 3 is an elevation of a railway passenger car equipped according to this invention;

Fig. 4 is a plan view, with the roof removed, of

the apparatus contained in the car shown by Fig. 3;

Fig. 5 is a transverse section of the central air duct shown by Fig. 4;

Fig. 6 is a sectional view through another type of air duct which may be used according to this invention, and

Fig. 7 is a sectional view showing the discharge portion of the duct of Fig. 6 modified slightly.

The railway passenger car of Figs. 3 and 4 has the air conditioning unit, indicated generally by 10, mounted in one end and in the roof zone of the car. The air may be discharged through the central supply duct 11 or the two longitudinal ducts 12, arranged one along each side of the car and indicated by the dash-dot lines of Fig. 4.

The details of the apparatus of Figs. 3 and 4 are shown by Figs. 1 and 2. The apparatus is seen to comprise the blower 13, which indraws fresh and recirculated air into the air conditioning unit 10, passes it over the heater or cooler coils within the unit, and discharges it through the supply ducts. The fan or blower 13 may be driven by the electric motor 14, which may be energized from a storage battery mounted on the car and/or from an axle-driven generator.

The extended surface cooling coils 15 are provided for cooling the air passing, in hot weather, through the unit, and may be supplied with ice water from an ice system, with brine from a secondary refrigeration system, or refrigerant such as freon may be expanded directly in the coils, used as evaporator coils. The steam coils 16 are provided for heating the air in winter, and a steam humidifier, or drip humidifier, may be associated with the steam coils to add moisture to the heated air when desired. The recirculated air enters the unit 10 and passes through the channel 17, which is arranged beneath the heating coils 16, cooling coils 15, and blower 13. The removable filters 18 are arranged to the rear of the heat exchange coils for filtering the air to be conditioned.

The recirculated air intake to the unit 10 opens into the air supply duct 19, which has a recirculated air inlet 20 at the floor line of the car, and the recirculated air inlet 21 in the roof zone of the car. The damper 22 may be adjusted manually or thermostatically to close off the recirculated air inlet 21 and open the recirculated air inlet in summer, or to close off the recirculated air inlet 20 and open the recirculated air inlet 21 in winter, thus allowing air to be drawn from the floor line or roof zone, as required for the most advantageous circulation of conditioned air.

As indicated by Fig. 4, a single central air duct 11 may be used, or two air ducts 12, one arranged adjacent each of the longitudinal sides of the car, 60 may be used. Fig. 5 is a cross section through the central duct 11 and illustrates one embodiment of an air duct, according to this invention, in which an equal static pressure is maintained throughout the length of the duct. The conditioned air from the unit is blown under pressure into the upper portion 23 of the duct. Dividing the upper portion 23 from the lower portion 24, is the dividing wall 25, in which are arranged the three small slits 26, which extend the length of 70 the duct. A plate perforated with round or rectangular holes may also be used. These slits are preferably not more than $\frac{1}{8}$ inch in width. In operation, a static pressure of approximately 0.2 inch of water extends in the area 23, the entire length of the duct. The air under static pres-

sure passes out through the small openings 27 and is converted from static to velocity energy. A static air pressure is again built up in the lower area 24, and the air is discharged from the discharge openings 27 under static pressure and at 5 a desirable low velocity. The openings 27 are horizontal slits extending the entire length of the duct, or, if desired, of course, may be of any desired length and may be spaced longitudinally or crosswise of the duct. With this arrangement, 10 the conditioned air is discharged under equal pressure and with equal velocity at both ends of the duct.

Figs. 6 and 7 illustrate the invention for equal air distribution applied to pairs of ducts extending 15 along the longitudinal sides of the car. The conditioned air from the unit is discharged under pressure into the area 28 of the longitudinal duct 12. The vertical side of the duct is provided with the small slit 29, which, in this embodiment, extends the length of the duct and, as stated in connection with the discussion of Fig. 5, the width of $\frac{1}{8}$ inch has been found suitable under actual operating conditions. The slit 29 discharges into the area 30, arranged to one side of 25 the duct 12, and this area 30 is provided with the discharge outlet 31. In operation, a static pressure of approximately 0.2 inch of water is built up in the area 28 all the way to the end of the duct. This static pressure is converted into velocity energy on passage of the air through the slit 29 into the area 30. In the area 30, a lower static pressure is again built up, and the static pressure, on discharging through the discharge outlets 31, is converted again into velocity energy, 35 and the air passes out into the car at low velocity.

Fig. 7 illustrates a modification of the arrangement of Fig. 6, utilizing the ordinary car lighting fixtures for the discharge of air from the pair of longitudinal supply ducts. To the 40 rear of the electric light bulb 32 of Fig. 6 is arranged the conduit 33, which receives and supports the socket of the bulb 32. This conduit may be provided with a narrow slit 34 through which the air under static pressure in the area 45 28 passes, and the area 35, within the conduit 33, may correspond to the area 30 associated (Fig. 6) with the duct 12. Arranged around the socket 36 of each bulb 32 is the opening 37 which corresponds to the discharge opening 31 50 of Fig. 6. In operation, the static pressure is converted into velocity energy on passage through the slit 34; is partially converted again into static pressure on passage of the air into the space 35; converted again into velocity energy 55 in the space 37, and is discharged at low velocity on passage into the car.

With the arrangements illustrated by Figs. 6 and 7, pairs of ducts are used and the air is discharged from one duct towards the opposite 60 duct, the streams of low velocity air discharged from the two associated ducts passing downwardly to the passenger space from the upper center of the car.

Whereas several embodiments of the invention 65 have been described for the purpose of illustration, it should be understood that the invention is not limited to the details described, since many modifications may be made by those skilled in the art without departing from the spirit of the 70 invention.

What is claimed is:

1. Air conditioning apparatus for a railway passenger car comprising an air conditioning unit mounted in one end and in the roof zone

of said car, means for conditioning the air passing through said unit, a relatively large longitudinal duct connecting with the discharge side of said unit, an auxiliary duct associated with said relatively large duct and receiving air therefrom, means for enabling the building up a substantial static pressure in said relatively large duct and for discharging the air therefrom at high velocity into said auxiliary duct, a plurality of electric light bulb receptacles extending through said auxiliary duct into said car, and means for discharging the air from said auxiliary duct into said car around said receptacles.

2. Air conditioning apparatus for a railway

passenger car comprising an air conditioning unit mounted in one end and in the roof zone of said car, means in said unit for chilling, dehumidifying air in and discharging air therefrom, a distributing duct connecting with the discharge side of said unit, a plurality of spaced electric light fixtures containing light bulbs, and means for discharging the air from said duct into said car through openings adjacent said fixtures whereby the discharged air, prior to entrance into the passenger space of said car, passes over and around said bulbs.
